DESIGN FOR AN INFANT'S TEETHING DEVICE

Marjorie Egerton Storey, Cambridge, England
Application July 25, 1947, Serial No. 140,516

In Great Britain July 1, 1946

Term of patent 14 years

(Cl. D83—1)

To all whom it may concern:

Be it known that I, Marjorie Egerton Storey, a subject of the King of Great Britain, and residing at Cambridge, England, have invented a new, original, and ornamental Design for an Infant's Teething Device, of which the following is a specification, reference being had to the accompanying drawing, forming part thereof.

Fig. 1 is a plan view of an infant's teething device embodying my new design;

Fig. 2 is an edge view taken from the bottom of Fig. 1; and

Fig. 3 is an edge view taken from the right of Fig. 1.

I claim:

The ornamental design for an infant's teething device, as shown.

MARJORIE EGERTON STOREY.
